(57) CLAIM

The ornamental design for a game wheel, as shown and described.

DESCRIPTION

FIG. 1 is a front perspective view of a game wheel showing our new design with a handheld mobile electronic device in broken lines;

FIG. 2 is a back perspective view thereof;

FIG. 3 is a front view thereof with a handheld mobile electronic device in broken lines;

FIG. 4 is a right side view thereof;

FIG. 5 is a left side view thereof;

FIG. 6 is a back view thereof;

FIG. 7 is a top view thereof; and,

FIG. 8 is a bottom view thereof.

The broken lines in the drawing are for illustrative purposes only and form no part of the claimed design. Specifically, the broken lines are provided to illustrate the environment in which the game wheel may be used.
